UNITED STATES PATENT OFFICE.

ALBERT STEIN, OF CHICAGO, ILLINOIS, ASSIGNOR TO A. STEIN & COMPANY, OF CHICAGO, ILLINOIS, A CORPORATION.

DESIGN FOR A DISPLAY-CABINET FOR CARTONS.

50,452.

Specification for Design.

Patented Mar. 13, 1917.

Application filed December 28, 1916. Serial No. 139,415. Term of patent 7 years.

To all whom it may concern:

Be it known that I, ALBERT STEIN, a citizen of the United States, residing at Chicago, in the county of Cook and State of Illinois, have invented a new, original, and ornamental Design for Display-Cabinets for Cartons, of which the following is a specification, reference being had to the accompanying drawing, forming part thereof.

The figure is a perspective view of a display cabinet for cartons showing my new design.

I claim:

The ornamental design for a display cabinet for cartons, as shown.

ALBERT STEIN.
